PUMP IMPELLER

Julius Kuttner, Beloit, Wis., assignor to Fairbanks,
Morse & Co., Chicago, Ill., a corporation of
Illinois

Application August 21, 1942, Serial No. 455,601

7 Claims. (Cl. 103—145)

This invention relates to improvements in fluid pumps of oscillating vane type, and has particular reference to an improved oscillating vane or impeller structure for pumps of this character.

An object of the invention resides in the provision of a pump vane or impeller formed of a light-weight metal alloy and constructed for strength and durability, the improved vane thereby being characterized by a low moment of inertia and contributing to greater pump efficiency through an appreciable decrease in the power required to operate the vane. According to the present invention, the vane is constructed from an alloy known to the trade as "Dow Metal," wherein the alloy has a predetermined composition particularly adapted to the formation of an oscillating pump vane.

Another object is to provide a novel and effective shaft mounting arrangement for the vane, which will afford a secure operating connection between the vane and its drive shaft.

Other objects and advantages attained by the present improvements will appear readily from the following description and accompanying drawings. In the drawings:

Fig. 1 is a view in sectional elevation, of a fluid pump illustrating the presently improved impeller vane therein;

Fig. 2 is a fragmentary sectional view of the pump and vane, as taken along the line 2—2 in Fig. 1;

Fig. 3 is an end elevation of the improved impeller vane;

Fig. 4 is a longitudinal sectional elevation thereof, as viewed from line 4—4 in Fig. 3;

Fig. 5 is a transverse section of the vane, as taken along line 5—5 in Fig. 4;

Fig. 6 is an end view of the vane, similar to the view of Fig. 3 but taken at the opposite end thereof, and

Fig. 7 is a longitudinal section through the vane hub, as taken along the line 7—7 in Fig. 4.

Referring to the drawings by appropriate characters of reference, there is illustrated by Fig. 1 a fluid pump denoted generally by the numeral 10, in which is embodied the improved oscillating vane or impeller 11 forming the subject of the present invention. Although the vane may be employed in pumps serving various purposes, the pump as shown herein, is of a character suitable for use with internal combustion engines to supply scavenging air to the engine cylinders. Since apart from the vane and its mounting on the pump shaft indicated at 12, the form and structural details of the pump do not concern the

present invention, such will be described only briefly.

The pump 10 which is illustrated somewhat diagrammatically, includes a casing structure designated generally by the numeral 14, providing a fluid chamber 15 in which the vane 11 oscillates. The chamber is divided by casing partitions 16 and fluid seals 17 between the partitions and the hub portion 18 of vane 11, to provide opposite pumping compartments 19 and 20 one for each of the vane arms 22. Communicating with the compartment 19 on the opposite sides thereof, are passages 23 which serve alternately as inlet and outlet passages for the compartment. Fluid as air, is admitted to the passages 23 on the suction strokes of the vane arm 22 in compartment 19, through unidirectional or one-way valves 24 from supply chambers 25 in communication with the atmosphere or other source of air. The air thus drawn into compartment 19 alternately on opposite sides of the vane arm 22, is discharged therefrom alternately into the passages 23 in response to the compression or discharge strokes of the vane arm, and thence through similar one-way valves 26 into a chamber 21, from which the air under pressure may be conducted to the engine cylinders. Similar passages 28 are associated with the other pump compartment 20, and include inlet valves 29 and outlet valves 30 providing respectively, one-way communication between the supply chambers 25 and the passages, and between the passages and a discharge chamber 32 which is similar to the discharge chamber 21.

With reference now to the improved oscillating impeller 11, this member is constituted by a unitary casting of a light weight, relatively soft metal alloy known to the trade as "Dow Metal," wherein the alloy has a composition especially suited to the formation of the impeller or vane, so as to afford a strong yet light-weight impeller having a desirably low moment of inertia. The alloy composition employed for this purpose, consists of the following elements in the proportions indicated:

Aluminum, substantially six (6) percent; manganese, substantially two-tenths (.2) of one percent; zinc, substantially three (3) percent, and the remainder magnesium. The vane as formed of this material, may be a solid unitary casting, but as preferred and herein illustrated, is of a cast cored construction to provide hollow blades or arms 22 which are strengthened in a manner presently to be described. The hollow arm formation affords a somewhat greater reduction in

weight of the completed vane, which is of importance to the present attainment of a vane having a desirably low moment of inertia.

The improved vane structure as shown particularly by Figs. 3 to 7, comprises a hub 18 of generally tubular form, and integral vane arms 22 extending radially from diametrically opposite sides thereof. Each arm is of hollow form as shown, providing imperforate side walls 33 joined by a wall 34 at the forward or tip end of the vane, and end walls 35 each apertured as at 36. The tip wall 34 may be rounded as shown, in conformity with the wall curvature of the pump chamber 15 in which the vane operates (Fig. 1). Within the hollow arm are a series of transverse partitions or webs 37 each by preference apertured at 38, these members serving to strengthen the vane arm and in particular, the side walls 33 thereof. As will be observed from Figs. 1, 3 and 5, each vane arm is appreciably tapered from the hub 18 convergently toward the tip wall 34, which with the removal of metal in the end walls 35 and partitions 37 in zones inwardly from the tip end of the arm, as to provide the respective apertures 36 and 38, thus serves to determine or locate the center of mass of the arm nearer the vane axis of oscillation. This last is a factor of importance to the attainment of a vane structure having a relatively low moment of inertia, as will be appreciated.

According to the present improvements, provision is made for effecting a positive and durable driven connection of the alloy vane to the shaft 12 the means for attaining this end being of a character to avoid direct key-connection between the shaft and the vane hub 18, which would require the provision of a substantially narrow and deep longitudinal slot or key-way in the relatively soft metal of the hub. As herein provided, a number of similar bushings 39 are integrally united with the hub 18 in the casting of the vane structure, which bushings are of suitable, hard material, as steel, each having key-ways 40 to receive keys 42 in the connection thereof to the shaft 12. The rigid cast connection of the bushings and vane hub 18 is assured in a most effective manner by the provision of opposed, rounded projections or lobes 43 on each bushing 39, which seat in correspondingly curved hub recesses 44 formed in casting the impeller with the bushings. In this manner, the bushing is integrally keyed to the vane hub such that the shearing forces in these zones resulting from rapid oscillation of the shaft and impeller, are desirably distributed to an extent such as to substantially preclude cracking of the soft metal hub 18.

The shaft 12 is projected through the hub bore 45 as shown by Fig. 2, to seat in the bushings 39, and is keyed to the latter elements by the keys 42. A raised shaft portion 47 formed inwardly adjacent the shaft end 48 which extends beyond the vane end 49, is closely received in a bearing seat 50 provided by an internal annular extension or projection 52 of the hub 18 at the vane end 49. In order to secure the vane structure against displacement longitudinally of the shaft, the latter is provided with an annular flange 53 near the shaft end 54, which seats in an annular recess 55 formed in the exposed edge 56 of the bushing 39 at the end 57 of vane hub 18 (Fig. 2). On the opposite end 48 of the shaft 12 is provided a collar 58 which abuts the hub projection 52 in a recess 59 formed therein. With the bushing 39 at the hub end 57 in firm abutment with the shaft flange 53, the collar 58 is clamped against the hub projection 52 and retained in such position by a lock nut 60 threaded on the shaft end 48 and acting against the collar through a shaft bearing assembly 62, as clearly appears in Fig. 2. Thus movement of the vane along the shaft 12 is thereby effectively precluded.

In the support of the vane shaft 12, the shaft bearing 62 above indicated, is received in a mounting socket or recess 63 formed centrally in one end wall 64 of the pump casing, while the opposite casing end wall 65 is provided with a projecting bearing support 66 carrying a sleeve bearing 67 for the end 54 of shaft 12. The shaft end 54 is extended outwardly beyond the bearing 67 to provide for driving connection to the oscillating vane, as from an operating part of the engine (not shown) with which the pump may be associated.

As will now appear, the present improvements concern the formation of an oscillating pump vane or impeller from light-weight "Dow Metal" alloy of the composition indicated, and the impeller connection to its operating shaft, whereby to characterize the vane by a relatively low moment of inertia, and by a strong and durable structure having a positive connection to its operating shaft, with the latter effected in a manner to avoid key-way slotting of the soft metal vane hub.

Having described a preferred embodiment of the present invention, the features thereof desired to be protected by Letters Patent are set forth in the following claims.

I claim:

1. An impeller of the character described, for a fluid pump, comprising a substantially tubular hub, impeller arms extending radially from said hub, and hub bushings each having at least one peripheral projection thereon, said hub and arms being formed as a unitary, integral structure with said bushings arranged at spaced intervals in said hub and having the projections thereon embedded in the hub.

2. An impeller of the character described, for a fluid pump having an impeller actuating shaft, the impeller comprising a substantially tubular hub, shaft-engaging bushings arranged in the hub, and impeller arms extending radially from said hub, said hub, arms and bushings being integrally united to form a unitary structure.

3. An impeller of the character described, for a fluid pump having an impeller actuating shaft, the impeller comprising a cast metal structure including a tubular hub having radially opposed vanes projecting therefrom, and a bushing adapted for connection to the shaft, embedded in said impeller hub, said bushing having projecting lobes thereon, seating in recesses therefor in the hub.

4. An impeller of the character described, for a fluid pump having an impeller actuating shaft, the impeller comprising a cast metal structure including a tubular hub and radially opposed vanes projecting therefrom, and a bushing adapted for connection to the shaft, provided with arcuate projections thereon, said bushing being integrally united with the hub in the casting of the impeller, with said arcuate projections seating in correspondingly arcuate recesses in the hub.

5. An impeller of the character described, for a fluid pump having an impeller actuating shaft, the impeller comprising a substantially tubular hub, shaft-engaging bushings arranged in the hub, and impeller arms extending radially from said hub, said hub and arms being formed as an integral structure, from a relatively soft, light-

weight metal alloy, with said bushings embedded in said hub.

6. An impeller of the character described, for a fluid pump having an impeller actuating shaft, the impeller comprising a substantially tubular hub, shaft-engaging bushings embedded in said hub, impeller arms extending radially from said hub, each thereof being of hollow form, and transverse strengthening elements within each arm.

7. An impeller for a fluid pump having an im-

peller actuating shaft, comprising a unitary structure including a tubular hub, shaft-engaging bushings arranged in the hub, and impeller arms extending radially from the hub, said impeller hub and arms being formed from a relatively soft, light-weight metal alloy containing about ninety percent magnesium, and the impeller further being characterized by a relatively low moment of inertia.

10

JULIUS KUTTNER.
